UNITED STATES PATENT OFFICE.

ALONZO C. CHAPLIN, OF CAPE ELIZABETH, ASSIGNOR OF ONE-HALF TO
D. W. CLARK & CO., OF PORTLAND, MAINE.

ICE-CUTTING MACHINE.

SPECIFICATION forming part of Letters Patent No. 271,220, dated January 30, 1883.

Application filed September 2, 1882. (No model.)

To all whom it may concern:

Be it known that I, ALONZO C. CHAPLIN, of Cape Elizabeth, in the county of Cumberland and State of Maine, have invented certain new and useful Improvements in Ice-Cutting Machines; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a top plan. Fig. 2 is an end view, showing the cutters. Fig. 3 is an end view, showing the ribber. Fig. 4 is a side elevation. Fig. 5 is a detail, showing the ribber and cutters in part section on the line *x* of Fig. 1.

Same letters show like parts.

My invention relates to machines for cutting off snow, slush, and useless portions from ice-cakes before packing them into ice-houses, and for ribbing the cakes, so that they will not freeze together when so packed.

My invention consists in the combination of an ice-carrying frame or frames set on endless bands or chains with a gaged or adjustable cutting-frame and its cutters, operated as herein set forth, and of the combination of a set of ribbers with said ice-carrying frame and gaged frame, as herein set forth.

a shows a slip such as are usually made, leading from the ice-field up into the packing-house. *b* is the cutter-carrying frame. It is V-shaped, as shown in the drawings. It is placed between four uprights, *c*, and parallel with the slip *a*, as seen in Fig. 4. It is suspended from the lever *e*, attached to the center of the crane *f*, rising from and attached to the frame in the manner seen in Fig. 1. It is held in balance, so as to be easily worked, by the cords and weights *g*, running over pulleys in the posts *c*. It is raised or depressed by the lever *e*. Each side of the V-shaped frame *b* is furnished with the cutter *g'*, bolted to the frame *b*, as shown in the drawings. The inner edge of the frame *b* is beveled, as shown, to receive the V-shaped cutters *g'*. The wide end of the frame *b* and the cutters *g'* are nearest to the lower end of the slip *d*, and the ice, as it is drawn up the slip, is first received at such wide lower

end. The frame *b* is secured to a cross-head, *h*, at the upper end by the clamps *i*. A cross-bar, *j*, at the lower end makes the frame strong and firm.

The action of the knives or cutters *g'* is to cut off slush and bad or imperfectly-frozen matter on the tops of the cakes and reduce them to a uniform thickness.

k are the ribbers. They cut shallow grooves 60 in the top surfaces of the cakes. The effect of this cutting is that they will not become frozen together when packed in the ice-house, and can thus be handled easily and without breaking.

The cutters *g''* are arranged on a bevel, as seen in the drawings, and bolted to the beam *b*, which is beveled to receive the said cutters. Two beams, *v*, extend—one on each side of the slip—from the ice-field to the door of the house 70 on the inclined slip. They are rabbeted at *l* to allow the endless chain *m* to pass easily up in and along them. At certain distances along the endless chains are attached the cross-bars *n*, extending across from one chain to the other, 75 attached to the chains and moved as they are moved. These bars constitute boxes or places in which to hold the blocks of ice and draw them up into the house and under the action of the cutters *g'*.

Strips *o* on the bottom of the slip, and extending longitudinally of it, furnish the tracks on which the cakes of ice slide as they are moved up into the house.

p are studs to hold the cutter-carrying frame 85 at any point of elevation above the slip, so that the ice can be evenly shaved or cut. There is one of these projecting from each of the posts or uprights *c*. A number of holes in these uprights allow of the pins being placed at different heights above the slip, and of their holding the frame *b* at such elevation. If a cake of ice come up the slip turned up edgewise, then the lever *e* can be employed to raise the frame *b* and allow the cake to pass under, and the 90 frame *b* can be immediately lowered again. The ribbers are attached, as seen in Fig. 5, at *k*. Thus cakes of uniform thickness, relieved of slush and other matter, and ribbed as described, can be delivered to the ice-packing 100 house with ease and rapidity.

The movement of the chains *m* can be pro-

duced by an engine or any well-known means. The metal plates g' serve to steady the cutters, and aid in carrying off the matter cut from the tops of the ice-cakes.

5 What I claim as my invention, and desire to secure by Letters Patent of the United States, is—

1. The combination of the frame b , cutters g'' , uprights c , crane f , lever e , chains m , and cross-bars n , as herein set forth.

2. The combination of the ribbers k , frame b , crane f , lever e , cross-head h and cross-bars n , and chain m , as herein set forth.

In testimony that I claim the foregoing as my own I affix my signature in presence of two ¹⁵ witnesses.

ALONZO C. CHAPLIN.
